SUNSHADE ATTACHMENT FOR A PAIR OF
SPECTACLES OR THE LIKE

Steve Boxer, 4414 Woodman Ave., Sherman Oaks, Calif.
91403, and Norman C. Bouse, 1655 Chelsea Road, San
Marino, Calif. 91108

Filed Oct. 4, 1965, Ser. No. 87,296

Term of patent 14 years

(Cl. D57—1)

FIG. 1.

FIG. 2.

FIG. 3.

FIG. 4.

FIGURE 1 is a front elevational view of a sunshade attachment for a pair of spectacles or the like showing our new design.

FIGURE 2 is a side elevational view thereof.

FIGURE 3 is a top plan view thereof.

FIGURE 4 is a rear elevational view thereof.

The broken line showing of the spectacles on the drawing, partially omitted in FIGURE 3 is for illustrative purposes only.

We claim:

The ornamental design for a sunshade attachment for a pair of spectacles or the like, substantially as shown and described.
